(75) Inventor: **Kenneth Richard Malsan**, Rexford, NY (US)

* cited by examiner

(73) Assignee: **Kenneth R. Malsan**, Rexford, NY (US)

Primary Examiner — Angela J Lee

(**) Term: **14 Years**

(57) **CLAIM**
The ornamental design for a display stand for a portable electronic device, as shown and described.

(21) Appl. No.: **29/373,346**

DESCRIPTION

(22) Filed: **Mar. 31, 2011**

FIG. 1 is a front left perspective view of the display stand for a portable electronic device showing my new design;

(51) **LOC (9) Cl. 14-02**

FIG. 2 is a front right perspective view thereof;

(52) **U.S. Cl. D14/447**

FIG. 3 is a right side perspective view thereof;

(58) **Field of Classification Search** D14/447,

FIG. 4 is another right side perspective view thereof;

D14/448, 451, 452, 432, 434, 439, 440, 457,

FIG. 5 is a front view thereof;

D14/460, 461, 239, 250, 251, 253, 217, 238.1;

FIG. 6 is a front perspective view thereof;

D3/218; D6/310, 312, 311, 406.3, 406.4,

FIG. 7 is a right side view thereof;

D6/406.5, 406.6, 419; 248/917-924, 688,

FIG. 8 is a left side view thereof;

248/441.1, 451, 454, 460, 463, 136, 149,

FIG. 9 is a bottom right side perspective view thereof;

248/150, 164, 166, 176.2, 176.3, 176.1, 346.03,

FIG. 10 is a bottom view thereof;

248/346.3; 361/679.02, 679.09, 679.21,

FIG. 11 is a top view thereof;

361/679.22, 379.26, 679.27, 679.28, 679.29,

FIG. 12 is a back view thereof;

361/679.3, 679.46, 679.47, 679.48, 679.55,

FIG. 13 is a back left side perspective view thereof;

361/679.56, 679.57, 679.58, 679.59, 679.6;

FIG. 14 is a front perspective view thereof, but shown in use

150/165; 224/929, 930; D13/108; D8/354

with a portable electronic device shown in broken lines;

See application file for complete search history.

FIG. 15 is a side view thereof;

FIG. 16 is another side view thereof;

FIG. 17 is another side view thereof;

FIG. 18 is another side view thereof;

FIG. 19 is another front perspective view thereof;

FIG. 20 is another front perspective view thereof;

FIG. 21 is top perspective view thereof; and,

FIG. 22 is a side perspective view thereof.

The broken line showing of the mounted mobile phone display item in FIGS. 14, 15, 16, 17, 18, 19, 20, 21 and 22 is for the purpose of illustrating an environmental structure and

forms no part of the claimed design.
